UNITED STATES PATENT OFFICE.

ROCCO A. CARLUCCI, OF WEST NEW YORK, NEW JERSEY.

STRINGED INSTRUMENT.

Application filed June 9, 1924. Serial No. 718,743.

This invention relates to stringed instruments and particularly to what are known as banjos; and the object of the invention is to provide an improved frame construction for instruments of the class specified whereby the greatest tone volume may be produced, and also whereby a clear and distinct tone may be produced; a further object of the invention being to provide an all metallic mounting for the parchment or vellum of the instrument whereby the most desirable banjo tones can be produced; a further object being to provide an improved shape or form to what is known as the rim 10 of the banjo and particularly to banjos of the resonator type; and with these and other objects in view the invention consists in an instrument of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a perspective view of a banjo made according to my invention;

Fig. 2 is a plan view of the construction shown in Fig. 1, parts being broken away and in section;

Fig. 3 is a partial section on the line 3—3 of Fig. 2;

Fig. 4 is a partial section on the line 4—4 of Fig. 2 and on an enlarged scale;

Fig. 5 is a section on the line 5—5 of Fig. 2 and on an enlarged scale;

Fig. 6 is a detail plan view of the part of a modified form of the frame construction;

Fig. 7 is a section on the line 7—7 of Fig. 6;

Fig. 8 is a plan view of another part of the frame construction in Fig. 6;

Fig. 9 is a section on the line 9—9 of Fig. 8;

Fig. 10 is a section on the line 10—10 of Fig. 8;

Fig. 11 is a view similar to Figs. 6 and 8 but showing another part of the frame construction; and,

Fig. 12 is a sectional detail view of another form of frame which I may employ; and,

Fig. 12^a is a partial sectional view similar to the section shown in Fig. 5 but showing

the modified form of construction shown in Fig. 12.

In the drawing I have shown for the purpose of illustration, one method of carrying my invention into effect, a banjo 15 of the resonator type and in Fig. 1 of the drawing I have indicated at 16 the usual finger-board over which the strings 17 are passed, said strings being secured to the tail piece 18 at one end and passed over the bridge 19 adjacent to said tail piece, and the tension or tune of which are controlled by the rotary adjustable tuning members 20 at the free end of the finger-board. The shank 21 of the finger-board is reduced and extends into the framework or rim 22 of the instrument in the usual manner.

My invention consists primarily in the construction of the frame or rim 22 and the several parts mounted in connection therewith or cooperating therewith, said parts including the parchment or vellum 23 and resonator or sound-board 24.

In the construction shown in Figs. 1 to 5 inclusive, the frame or rim 22 is composed of a rim or body member 25 preferably composed of the wood usually employed for this purpose and, in practice, I provide the outer face of the rim or body 25 with vertically arranged and circumferentially spaced recesses 26 which are arc-shaped or semi-circular in form in cross section in the construction shown, and mounted on the rim 25 is a sheet metal facing member 27 which forms a facing or covering for the outer face of the rim 25 and is fashioned to fit and conform with the contour of the periphery of said rim or provided with semi-circular portions 27^a as clearly shown in Fig. 2 of the drawing. The member 27 may be made from an elongated strip of sheet metal fashioned into substantially corrugated formation to fit snugly within and over the contour of the rim 25, and the ends of which terminate where the finger-board passes through the rim 25. The member 27 is secured in position by a number of screws 28 passed through the arc-shaped portions thereof and into the rim 25, and the rim 25 and member 27 constitute the frame or rim of the banjo in connection with which the associated parts are mounted.

As above stated, the shank 21 of the finger-board passes through the frame 22 or the rim 25 thereof, said member being provided with an aperture 29 for this pur-

pose, as clearly shown in Fig. 3 of the drawing, and the inner end of the shank 21 extends into a bracket 30 and is held therein by a screw 31 in the usual or any desired manner, and the shank is also reinforced and rigidly fixed in position by a screw 32 which passes through a bracket 33 and into said shank where the shank passes through the aperture 29. Mounted upon the top peripheral portion of the frame 22 is a body ring 34 of comparatively thin metal, and this ring passes over the projecting portions 25^a of the rim 25 formed by the recesses 26 and the portions of the facing member 27 which pass over said projections 25^a are cut out to receive the ring 34 and to limit the downward movement thereof by reason of shoulders 35, one of which is shown in Fig. 4 of the drawing, and said shoulders serve to hold the body ring 34 in proper position with the upper end thereof projecting a predetermined distance above the frame 22 or the member 25 thereof.

The body ring 4 forms one part of a parchment or vellum support, the other part being in the form of a tension ring 36 of greater diameter than the body ring 34 and having a peripheral groove 37 in the face thereof, which groove is recessed as shown at 38 to receive hook-shaped ends of tension rods or bolts 39.

The parchment or vellum 23 is beaded in the periphery thereof in the usual way and provided with a skin hoop 40 within said bead, and the parchment is placed between the body ring 34 and tension ring 36 as clearly shown in Fig. 4 of the drawing in supporting the same in proper position and in placing the same under tension. The parchment 23 is mounted upon the usual tone resonance ring 41 positioned inwardly of the body ring 34 and tension ring 36, and mounted upon and spaced above the frame 22, said ring having a plurality of pins 42 which pass into the frame 22 and the top face of the frame is provided with spaced supporting members 43 upon which the tone ring 41 rests.

The periphery of the lower end portion of the frame 22 or the rim 25 thereof where the projections 25^a are located is recessed to permit of the passage of a horizontal ring member 44 thereover and to bear against the shoulders 45 formed by said recess, and by cutting away that portion of the member 27 which would normally cover the recessed portions of the projecting members 25^a as clearly shown in Fig. 4 of the drawing.

When the ring member 44 is placed in position a plurality of screws or bolts 46 are passed outwardly through the frame 22 and engage nut members 47 mounted in juxtaposition to and bearing on the lower faces of the ring member 44 to retain the same in proper position, and the nut members 47 seat

upon the recesses in the outer faces of the members 25^a as clearly shown in Figs. 2 and 4 of the drawing.

The tension bolts 39 are threaded at their lower end and pass downwardly through apertures in the horizontal ring member 44 and through corresponding apertures in the nut members 47 and nuts 48 are mounted on the protruding ends of said bolts whereby the same may be drawn into position to provide the proper tension to the parchment or vellum in the usual manner.

The horizontal ring member 44 projects beyond the frame 22 as well as beyond the parchment mounted on the frame to form a support for the resonator 24 and is preferably provided with circumferentially spaced apertures 49 of any ornamental shape or form through which the sound from the resonator is free to pass. The ring member 44 sets in a recessed portion 24^a of the resonator and rests upon a cushion 24^b on the shoulder formed by the recess 24^a. Two or more brackets 50 are secured to the resonator in spaced relation in connection with which headed screws or bolts 51 are mounted, the heads of said screws or bolts passing through the apertures 49 in the ring member 44 and cooperating with said ring to lock the resonator in position as clearly illustrated in Figs. 2 and 5 of the drawing.

With the form of construction above described, it will be noted that the parchment or vellum has an all metallic mounting in connection with the rim or frame 22 which is desirable in instruments of the class shown and described, and it will also be noted that by providing the circumferential spaced recess in the periphery of the frame 22 a greater volume of tone may be passed from the resonator outwardly through the chambers formed by the recesses in said frame than would be the case if said recesses were not employed, and by reason of this construction the volume as well as the clearness is materially improved and, in addition, to the utility and practicability of the recesses in the frame 22 a very neat attractive and finished appearance is provided to the complete instrument, the concave recess representing tubular formations about the periphery of the banjo frame and appearing above the resonator, the projecting members 25^a of the rim 25 being covered by the usual tension bolts 39.

The construction of the frame 22 above described will be very strong and durable and by reason of the fact that a strip of substantially the same width throughout may be employed in forming the facing member 27 the cost of manufacture thereof is simplified and the cost is not prohibitive, and while the form of construction above described is a vast improvement over the present type of frame or rim construction

from the standpoint of the tone of the instrument primarily, this can further be improved.

In Figs. 6 to 11 inclusive I have shown a modification in which I substitute for the rim 22 and the rim 25 and member 27 thereof, an all sheet metal frame or rim 52 which is composed of a comparatively heavy strip of sheet metal fashioned to form a ring-shaped body having circumferentially spaced concavo-convex portion 53, the concave faces being directed outwardly and being subdivided by spaced rib members 54, the outer faces of which are recessed at the top thereof as shown at 55 in Fig. 9 of the drawing, and at the bottom thereof as shown at 56 in said figure, the ring 34 being adapted to be placed in the recesses 55 while the horizontal ring member 44 is adapted to be placed in the recesses 56. In other words, instead of employing a frame composed of a wooden ring member 25 and a thin sheet metal facing 27, the entire frame is composed of sheet metal which is fashioned to provide the proper seats and bearings for the rings 34 and 44. With this construction the bolts 39, 46 as well as the nuts 47 and 48 are mounted in the same relative position as in the construction shown in Figs. 1 to 5 inclusive.

With the construction shown in Figs. 6 to 11, the tone ring 41 is mounted in position and spaced above the frame 52 by pins 57 mounted in connection with the tone ring 41 at spaced intervals, and the pin 57 being recessed as shown at 58 to engage the concave faces of the frame 52, or the members 53 thereof, and the pins 57 will operate to properly space and center the ring 41 in position.

The mounting of the shank 21 of the finger-board in and to the frame 52 may be accomplished in any desired manner but, in Figs. 6, 7, and 8, I have shown one method of accomplishing this result and in Figs. 6 and 7 I have shown a bracket 59 welded or otherwise secured to the frame 52 and through which the shank 21 is passed and secured by the screw 32, and in Fig. 11 I have shown a bracket 60 to receive the end of the shank 21 and with which said shank may be coupled and the bracket 60 welded or otherwise secured to the frame 52.

With the construction shown in Figs. 6 to 11 inclusive, it will be apparent that the only obstruction to the sound vibrations coming from the resonator will be the thickness of the frame or rim 52 thus producing the greatest possible volume and clearance of tone in that all of the wood structure of the frame has been omitted, this construction will also prevent the warping of the frame which has been experienced in instruments of this class, and by reason of the fact that the frame 52 may be fashioned

from sheet metal the production and cost of manufacturing the frame of instruments of the class described may be materially reduced and yet a very strong, durable and practical frame construction is provided as well as a frame construction which has by far greater advantages than other frames of its class.

In Figs. 12 and 12^a I have shown another modification in which I provide a frame 61 which may be cast from metal by the use of suitable molds or dies and in which the body ring 34 is formed integral with the frame as indicated at 61^a, and the ring 44 is integral with the frame as indicated at 61^b, the frame being provided with spaced apertured enlargements or bosses 61^c to take the place of the bolts 46 and nuts 47, the bolts 39 passing through the apertures in the bosses 61^c and also that the tone ring 41 is formed integral with the frame 61 by spaced web structures 61^d. In other words with the construction shown in Figs. 12 and 12^a of the drawing all of the parts 22, 25, 27, 34, 41, 44, 46 and 47 of the construction shown in Figs. 1 to 5 inclusive, and, if desired, the brackets 30 and 33 may be all formed integral or in a single unit, and the corresponding parts of the construction shown in Figs. 6 to 11 inclusive may be correspondingly formed integral.

The frame as partially illustrated in Figs. 12 and 12^a as above set out may be cast or otherwise formed and preferably die-cast of a comparatively light and yet strong and durable metal or a metal suitable for instrumental purposes, and while I have shown certain details of construction for carrying my invention into effect, it will be understood that I am not necessarily limited to these details, and various changes therein and modifications thereof may be made, within the scope of the appended claims, without departing from the spirit of my invention or sacrificing its advantages.

Having fully described my invention what I claim as new and desire to secure by Letters Patent, is:—

1. A banjo of the class described, the parchment supporting rim of which comprises a continuous circular body provided in the periphery with circumferentially spaced recesses extending through the top and bottom faces of said rim and forming about the periphery of the rim, spaced sound transmission chambers.

2. A banjo of the class described, the parchment supporting rim of which comprises a continuous circular body provided in the periphery with circumferentially spaced recesses extending through the top and bottom faces of said rim and forming about the periphery of the rim, spaced sound transmission chambers, and means for supporting a parchment in connection with the

- rim in such manner that the periphery portion of the parchment extends over and encloses the upper end portions of the recesses in said rim.
5. An integral banjo frame construction comprising a rim, body ring and resonator supporting ring.
6. An integral banjo frame construction comprising a rim, body ring, resonator supporting ring and tone ring.
7. A rim for instruments of the class specified, comprising a ring-like body having a comparatively wide face traversing the horizontal plane of the rim, the periphery of said rim being provided with circumferentially spaced recesses opening outwardly through the wide face of the rim and through the top and bottom faces thereof.
8. A rim for instruments of the class described comprising a substantially circular metal body having a comparatively wide peripheral face fashioned to form circumferentially spaced recesses and rib-like members, the longitudinal plane of said recesses and rib members traversing the horizontal plane of the rim, and said recesses opening outwardly and through the top and bottom faces of said circular body.
9. A sheet metal rim for banjos, means on said rim adjacent the upper edge portion thereof for forming a seat for a metal parchment retaining ring, a parchment, another metal ring cooperating with said first named ring and parchment to provide an all metal mounting for the parchment, means for adjusting the position of the second named ring for placing the parchment under tension, and said rim being fashioned to form a seat adjacent the lower edge portion thereof to provide means for mounting and retaining a resonator in fixed and spaced relation with reference to said rim.
10. A banjo parchment supporting rim of the class described comprising a unitary arc-shaped body fashioned to form on the outer periphery face thereof concavo-convex recesses spaced circumferentially of the rim, said recesses extending entirely through the transverse plane of the rim.
11. A banjo rim of the class described comprising an arc-shaped body fashioned to form on the outer periphery face thereof concavo-convex recesses spaced circumferentially of the rim, said recesses extending entirely through the transverse plane of the rim, a metal strip mounted on the periphery of said rim and forming a facing for the contour thereof.
12. A banjo rim of the class described comprising an arc-shaped body fashioned to form on the outer periphery face thereof concavo-convex recesses spaced circumferentially of the rim, said recesses extending entirely through the transverse plane of the rim, a metal strip mounted on the periphery of said rim and forming a facing for the contour thereof, and means for securing said metallic strip to said rim.
13. A banjo frame construction comprising a unitary rim and ring body, and said rim being provided in the periphery thereof with circumferentially spaced recesses forming therebetween rib members, said recesses being semi-circular in form and opening outwardly and through the top and bottom faces of the rim.
14. A banjo frame construction comprising a unitary rim and ring body, and said rim being provided in the periphery thereof with circumferentially spaced recesses forming therebetween rib members, said recesses being semi-circular in form and opening outwardly and through the top and bottom faces of the rim, and a resonator supporting ring integral with said rim.
15. A banjo of the class described, the rim of which is provided in the periphery with circumferentially spaced recesses extending through the top and bottom faces of said rim and forming about the periphery of the rim, spaced sound transmission chambers, means for supporting a resonator in spaced relation with reference to said rim, means for supporting a parchment in connection with the rim in such manner that the periphery portion of the parchment extends over and encloses the upper end portions of the recesses in said rim, means adjustably mounted in connection with the rim and cooperating with said last named means for retaining the parchment in position under tension, and a resonator supporting ring and tone ring integral with said rim.
16. A banjo rim provided in the periphery thereof with circumferentially spaced recesses forming therebetween spaced rib members, said recesses opening outwardly and through the top and bottom faces of the rim, and the rib portions of the rim being recessed, and a body ring mounted in one of the last named recesses and projecting above the top face of the rim.
17. A banjo rim provided in the periphery thereof with circumferentially spaced recesses forming therebetween spaced rib members, said recesses opening outwardly and through the top and bottom faces of the rim, and the rib portions of the rim being recessed, a body ring mounted in one of the last named recesses and projecting above the top face of the rim, and a resonator supporting ring mounted on the other of said recesses and projecting upwardly and radially from the rim to support a resonator of greater diameter than the rim in connection with said rim in spaced relation.
- In testimony that I claim the foregoing as my invention I have signed my name this fifth day of June, 1924.
- ROCCO A. CARLUCCI.
